MAST MOUNTED LAMP HOUSING

Josef Müller, Neheim-Hüsten, Germany, assignor to Tri-lux-Lenze KG, Neheim-Hüsten, Germany

Filed Mar. 18, 1965, Ser. No. 84,344

Term of patent 14 years

(Cl. D48—31)

FIG. 1.

FIG. 5.

FIG. 3.

FIG. 2.

FIG. 4.

FIG. 6.

FIG. 7.

FIG. 8.

FIG. 9.

FIG. 12.

FIG. 10.

FIG. 11.

FIG. 1 is a perspective view of the design;
FIG. 2 is a top plan view thereof;

FIG. 3 is a side elevation of FIG. 1 taken in the direction of the front view on FIG. 1.

FIG. 4 is an end elevation of FIG. 1 taken in the direction of the left hand side view of FIG. 1.

FIG. 5 is a rear elevation of FIG. 1 taken in the direction of the right hand side view of FIG. 1.

FIG. 6 is a bottom view of FIG. 1 taken in the direction of the bottom view of FIG. 1.

FIG. 7 is a perspective view of another form of the invention;

FIG. 8 is a top plan view thereof;

FIG. 9 is a side elevation of FIG. 7 taken in the direction of the front view of FIG. 7.

FIG. 10 is an end elevation taken in the direction of the left hand side of FIG. 7.

FIG. 11 is a rear elevation taken in the direction of the right hand side of FIG. 7.

FIG. 12 is a bottom view taken in the direction of the bottom view of FIG. 7.

The supporting post elements throughout the figures are shown broken away to indicate indeterminate length.

I claim:

The ornamental design for a mast mounted lamp housing, as shown and described.
